UNITED STATES PATENT OFFICE.

MATTHEW B. OWENS, OF NAPAVINE, WASHINGTON.

CONCRETE-BLOCK MACHINE.

1,410,832.

Specification of Letters Patent. Patented Mar. 28, 1922.

Application filed June 7, 1921. Serial No. 475,578.

To all whom it may concern:

Be it known that MATTHEW B. OWENS, citizen of the United States, residing at Napavine, in the county of Lewis and State 5 of Washington, has invented certain new and useful Improvements in Concrete-Block Machines, of which the following is a specification.

My invention relates to a machine for 10 molding concrete blocks, such as are used in the construction of walls of houses, and one of the objects of the invention is to provide a machine of this character for making a moisture proof block. The ordinary concrete 15 core block has been found unsatisfactory for the walls of houses, on account of the fact that it is not moisture proof. This has led to the development of a two part block connected together by wires, so that when built 20 up into a wall, there is a continuous air chamber through all the walls of the building. A block of this type is at present made in what is known as a side face machine, which necessitates making the front half 25 of the block out of the best material so as to get a block which will have a good external appearance.

An object of my invention is to provide a machine whereby a block having as good 30 an external appearance may be made by the use of only a relatively small quantity of the best material. This I accomplish by making the block in what I designate as a down face core machine.

With these general objects in view, my 35 invention consists in certain novel and peculiar features of construction and combination of parts as hereinafter described and claimed; and in order that it may be fully 40 understood reference is to be had to the accompanying drawings, in which similar reference characters indicate corresponding parts in all the views.

Referring to the drawings,

Fig. 1 is a plan view of the machine; 45 Fig. 2 is a vertical section on the line 2—2,

Fig. 1;

Fig. 3 is a vertical section on the line 3—3 of Fig. 1;

Fig. 4 is a perspective view of one of the 50 end cores and

Fig. 5 is a perspective view of the finished block.

In the drawings 1 is the supporting stand 55 of the machine to which is secured the rectangular frame 2, comprising a strut 3 to

which is connected by hinges 4 the mold box 5. The said mold box comprises end members 6 having openings 7 through which move the end cores 8. Through openings 10 60 in the side members 9 of the mold box moves a side core 11.

The end cores 8 are wedge shaped and are provided on their sides with guide grooves 12 which cooperate with guide cleats 13 secured to the inner side of the side members 9. For limiting the outward movement of the end cores, I provide stops 14 secured to the end members, to engage the end of the closed slots 15 on the sides of the said end 70 cores. The inner end of the end cores are shaped to provide a guide groove 16 which cooperates with a guide 17 carried by the center core.

For holding the metal tie members 19 in 75 suitable position, grooves 20 are provided in the face of the end cores.

The bottom 21 of the mold box, on its inner side, has a molding strip 22 to give the appropriate shape to the face of the molded 80 block. Depending from the top of the stand 1 at each end of the mold box, are members 23 upon which is pivotally mounted the hand levers 24, the said levers having a slot 26 engaging a pin 25 carried by the extension 27 of the end core.

Secured to the frame 2 are supports 28 for the guide bars 29; reciprocating in the said guide bars are the guides 17 of the center core which have extensions 30 for also engaging the said guide bars. For reciprocating the center core, there is provided a hand lever 31, pivoted at its lower end to a member 32 rigid with the frame 2, and pivotally connected intermediate its ends 95 with a link 33, which in turn is pivotally connected to the center core through an extension 34.

The sides 5 of the mold box are detachable, spring clamps 35 engaging the end members 100 to hold the box in assembled position. One of the sides 5 may be provided with stakes 36 engaging apertures 37 to facilitate guiding and holding the side in place.

The operation of my invention is as follows: The side and end cores are withdrawn from projecting into the box. A layer of the best material is sifted into the bottom of the mold and then sufficient of the ordinary material to reach up to the guide cleat 110 13. The two end cores are then pushed into the box by the hand levers 24 and the

metal tie members 19 inserted in place as shown. The center core 11 is then moved into place, the sharpened lip 38 cutting away the excess material. The box is then 5 filled level, a suitable amount of tamping having been given to compress the material. To remove the block, the center core is withdrawn; taking hold of the end levers 24, the box is turned on the hinge 4 through 10 90 degrees until it rests on the supporting frame 2, as shown in dotted line position. The end cores are then withdrawn, the clamps 35 taken off and the top side 5 removed, whereupon the molded block as 15 released will have the shape shown in Fig. 5, the front face of the same being of superior material to the main body thereof.

From the above description it will be apparent that I have produced a device of the 20 character described, which possesses all the features enumerated as desirable, and while I have illustrated and described the preferred form of the invention, it will be understood that I reserve the right to all 25 changes properly falling within the scope and spirit of the appended claims.

There what I claim as new and desire to secure by Letters Patent is:

1. A concrete block machine comprising a mold box, end and side cores adapted to reciprocate therein, the said cores uniting within the mold box to provide a horizontal partition for making a two part block.
2. A concrete block machine comprising a mold box, end and side cores adapted to reciprocate therein, the said cores uniting within the mold box to provide a horizontal partition for making a two part block, and apertures through the partition for tying 35 means, to secure together the two parts of the block.
3. A concrete block machine comprising a mold box, end and side cores adapted to reciprocate therein, the said cores uniting within

the mold box to provide a horizontal partition for making a two part block, the bottom of the mold box being provided with molding means to give the appropriate shape to the face of the block. 45

4. A concrete block machine comprising a mold box, a pair of end cores adapted to reciprocate therein, and a side core adapted to reciprocate between the end cores to provide a horizontal partition for making a 50 two part block.

5. A concrete block machine comprising a mold box, a pair of end cores adapted to reciprocate therein, and a side core adapted to reciprocate between the end cores to provide a horizontal partition for making a 60 two part block and apertures between the said cores for tying means, to secure together the two parts of the block.

6. A concrete block machine comprising a support, a mold box rotatably mounted 65 thereon, end cores carried by the mold box and adapted to reciprocate therein, a side core carried by the support and adapted to reciprocate between the end cores to provide a horizontal partition for making a 70 two part block.

7. A concrete block machine comprising a mold box, a pair of end cores adapted to reciprocate therein, and a side core adapted to reciprocate between the end cores and transversely thereto to provide a horizontal 75 partition for making a two part block.

8. A concrete block machine comprising a support, a mold box rotatably mounted thereon, end cores carried by the mold box 80 and adapted to reciprocate therein, a side core carried by the support and adapted to reciprocate transversely between the end cores to provide a horizontal partition for making a two part block.

85 In testimony whereof I affix my signature.

MATTHEW B. OWENS.
